UNITED STATES PATENT OFFICE

146,363

DESIGN FOR A HOUSEHOLD FOOD BEATER

Leroy J. Jagow, Cheektowaga, N. Y.

Application January 22, 1946, Serial No. 125,832

Term of patent 14 years

(Cl. D44—29)

To all whom it may concern:

Be it known that I, Leroy J. Jagow, a citizen of the United States, residing at Cheektowaga, in the county of Erie and State of New York, have invented a new, original, and ornamental Design for a Household Food Beater, of which the following is a specification, reference being had to the accompanying drawings, forming part thereof.

In the drawings:

Fig. 1 is a front elevational view of a household food beater embodying my new design, the rear elevational view being substantially identical thereto.

Fig. 2 is a side elevational view thereof.

Fig. 3 is a side elevational view, viewed from the opposite side shown in Fig. 2.

Fig. 4 is a top plan view with the crank omitted.

Fig. 5 is a sectional view through the handle casing, this view being taken on line 5—5, Fig. 3.

I claim:

The ornamental design for a household food beater, as shown.

LEROY J. JAGOW.
